ATTORNEY

UNITED STATES PATENT OFFICE.

WILLIAM RALPH EMERSON, OF BOSTON, MASSACHUSETTS, ASSIGNOR TO
THE MEYER-SNIFFEN COMPANY, (LIMITED,) OF NEW YORK, N. Y.

DESIGN FOR A WATER-CLOSET BOWL AND STANDARD.

SPECIFICATION forming part of Design No. 18,441, dated July 10, 1868.

Application filed November 14, 1887. Serial No. 255,166. Term of patent 7 years.

To all whom it may concern:

Be it known that I, WILLIAM RALPH EMERSON, a citizen of the United States, and a resident of Boston, in the county of Suffolk and State of Massachusetts, have invented and produced a new and original Design for a Bowl and Standard for Water-Closets, of which the following is a specification, reference being had to the accompanying engraving, forming a part thereof.

The engraving shows in perspective a water-closet bowl and standard embodying my design, the leading features of which are, first, the basket-work ornamentation of the bowl, and, secondly, the bulrushes ornamentation of the standard.

The upper portion or rim of the bowl is provided with a border, A, consisting of a series of parallel undulating ribs or beads.

The bowl is provided with decoration, B, in imitation of basket-work. This ornamentation

conforms to the curvature and shape of the bowl and is a prominent part of the design. Below the ornamentation B is provided a band, C, consisting of latticed bars. The base or standard of the structure is provided with embellishment, D, in representation of bulrushes, and a wave-like border, E, similar to that at the perimeter of the bowl.

What I claim, and desire to secure by Letters Patent, is—

The design for the surface ornamentation of the water-closet bowl and standard, as herein shown.

Signed at Boston, in the county of Suffolk and State of Massachusetts, this 10th day of November, A. D. 1887.

WILLIAM RALPH EMERSON.
